COLLAPSIBLE LAST

George F. Ryan, South Peabody, Mass.; Beatrice Z. Ryan, executrix of said George F. Ryan, deceased, assignor to Ryan & Burke Machine Co., Inc., Lynn, Mass., a corporation of Massachusetts

Application November 13, 1950, Serial No. 195,265

10 Claims. (Cl. 12—136)

1

This invention relates to lasts for use in the shoemaking industry and comprises an improved last constructed and arranged to collapse freely and quickly, and at the same time having novel connecting mechanism that is effective to hold the last solidly in locked condition with an exceptional degree of firmness and security. On account of its quick collapse it is particularly useful in the manufacture of slip lasted shoes, but it is also well adapted and useful in manufacturing welt and cemented shoes where the last must be subjected to severe pressure in the sole laying and other operations of the manufacturing process.

For many years manufacturers have sought for a satisfactory last construction permitting a quick and substantial collapse and shortening of the last in order that it may be withdrawn from the lasted upper without undue strain, and which also will insure the lengthening of the last after it has been fully introduced into the upper in the case of slip lasted shoes.

Another essential requirement is that the operations of locking and unlocking the last should be capable of being effected instantaneously and without requiring any extended manipulation on the part of the operator. All these conditions are advantageously fulfilled in accordance with the novel construction of my invention.

In one aspect it is characterized by connecting mechanism comprising an anchor pin in each part of the last and tension means for limiting separation of said pins including, in part, one toggle link of a pair which have the function of forcing the said pins apart and holding them locked in this condition with the last fully extended. The tension means, as herein shown, comprises a tension link directly connected with one of the anchor pins and a pair of toggle links connected at their opposite ends to the tension link and to the other of said pins at an intermediate point. One of the toggle links is arranged to rock about an anchor pin and has contact surfaces lying on both sides of the axis of the anchor pin so that the toggle may be readily broken or straightened by pressure on one or the other of these contact surfaces. The second link of the pair has a face which is engageable with the other anchor pin so that when the toggle links are straightened, the two anchor pins are forced apart by toggle action to relative positions of extreme separation. So long as they are held in this position, the last is locked in expanded condition and when the toggle is broken the last is quickly and substantially shortened.

5 The connecting mechanism of my invention has the further advantage that it may be constructed principally out of sheet steel stampings which may be produced economically and which may be conveniently retained in narrow slots formed in the contiguous faces of the last parts. Such slots are found in lasts already manufactured commercially, and accordingly the connecting mechanism of my invention requires no 10 unusual or extensive preparation of the last parts. Moreover, it has no tendency to split the last since the slots containing it may be surrounded by an ample thickness of wood.

These and other features of the invention will 15 be best understood and appreciated from the following description of a preferred embodiment thereof selected for purposes of illustration and shown in the accompanying drawings, in which:

Fig. 1 is a view in elevation, partly in longitudinal section, showing the last in extended position upon a jack,

Fig. 2 is a fragmentary sectional view showing particularly the unlocking pin of the jack.

Fig. 3 is a view corresponding to Fig. 1 but 20 showing the jack in collapsed position,

Fig. 4 is a fragmentary sectional view corresponding to Fig. 2 showing the unlocking pin in raised position,

Fig. 5 is an exploded view showing two of the 25 links,

Figs. 6 and 7 are fragmentary views corresponding to Figs. 1 and 3 but on a larger scale,

Fig. 8 is a view of the connecting mechanism, partly in section, as seen from above and on a 30 greatly enlarged scale,

Fig. 9 is a sectional view on the line 9—9 of Fig. 10, and

Fig. 10 is a view in elevation of the locking mechanism on the scale of Fig. 8.

40 The last comprises a forepart 10 and a heel part 11 of conventional shape separated by a diagonal cut formed with a shoulder near the cone of the last. The two last parts are provided with registering slots extending inwardly from their meeting faces and in these slots is mounted the connecting mechanism. This

comprises a main link 12 formed by folding on itself a piece of sheet steel so as to provide spaced side members and these members are provided with registering longitudinal slots 13. The link 12 is of double construction throughout its whole extent, the fold vertex 14 being formed at the forward end of a substantially rectangular portion of the link. This merges rearwardly into a hook-shaped portion as well

shown in Fig. 5. The recess which defines the hooked portion has a pair of spaced cavities 15 and 16 therein and a hole 18 for a pivot pin connecting the main link to the toggle links as will presently appear. The anchor pin 19 of the forepart passes through the slot 13 of the main link and is freely movable therein.

Toggle links 20 and 21 are pivotally connected at one end to the rear end of the main link. The link 20 is formed with a flange or pin 22 at its free forward end which has two functions, it provides a guiding connection with the slot 13, and it provides a contact face for engaging and pushing the anchor pin 19 outwardly in the slot. The other end of the link 20 has a circular periphery fitting a corresponding socket in the periphery of the other toggle link 21 and is provided with a circular aperture 23.

The other toggle link 21 has a centrally disposed aperture 24 which may be slightly elongated and which receives the anchor pin 29 of the heel part. It will thus be seen that the link 21 is pivotally mounted to rock on this pin. It is also provided with a hook-shaped connecting element 25 which is received in the circular aperture 23 of the link 20 and serves to maintain the knuckle joint of the toggle. The complementary curved surfaces of the two links in this joint provide an effective pressure transmitting connection, while the hooked element 25 prevents disengagement of the links. The link 21 is also provided at its rear end with a pivot hole 27 for the reception of a pivot pin 28 which passes through both sides of the main link 12 and connects the toggle links thereto. It will be apparent that the recess in the main link 12 affords clearance for the operative movement of the toggle links as will be seen by comparing the position of the toggle links in Figs. 1 and 3 or in Fig. 10. When the toggle links are straightened as shown in Fig. 1, the anchor pin 19 is pushed to the extreme limit permitted by the slot of the main link 12. In this position the toggle is closed an infinitesimal amount beyond its dead center position so that the toggle is thus locked in its extended position. This is governed by engagement of the anchor pin 29 in the cavity 15 of the main link. On the other hand, when the toggle is broken, its limiting position is determined by engagement of the anchor pin 29 with the cavity 16. When the toggle is broken to the position shown in Fig. 3, the anchor pin 19 in the forepart of the last is released and the two parts of the last are therefore entirely free to move into shortened relation in the direction determined by the shape of their meeting faces.

The toggle links above described may be operated in any convenient manner as, for example, by a jack 30 herein illustrated. This includes a spindle 31 adapted to enter the thimble of the last in the usual manner, and a locking pin 32 mounted for vertical movement in the jack in a path so directed that it will engage the inner end of the toggle link 21 when the latter is in broken position. When the locking pin 32 is elevated, the link 21 is rocked about the anchor pin 29 and the toggle straightened. The locking pin 32 rests upon a slide 33 having a wedge-shaped surface so located as to elevate the locking pin 32 when the slide is pushed toward the left as shown in Figs. 2 and 4.

The jack also contains an unlocking pin 34

guided in a movement such that it engages the outer end of the toggle link 21 when it is elevated so that it serves to rock the toggle link 21 in a clockwise direction and break the toggle. The unlocking pin is operated by a corresponding wedge surface in the slide 33 and these two surfaces are so located that when the locking pin is elevated the unlocking pin is free to drop, and vice versa.

From the foregoing description it will be clear that a last equipped with the improved connecting mechanism of my invention makes the insertion of the last fast and effortless in pre-fitted uppers. It eliminates strained or broken back seams due to last removal, makes last removal easier and quicker, and so simplifies and speeds up relasting. When the last is closed after insertion, the driving power of the toggle stretches the upper to its full length from toe to heel resulting in a tight top line and a snug fit in the heel and toe portions of the upper. The resulting easier relasting can be carried out without detriment to the fine lasted lines of the shoe in the manufacture of Littleways or McKays.

Having thus disclosed my invention and described in detail an illustrative embodiment thereof, I claim as new and desire to secure by Letters Patent:

- 30 1. A collapsible last having heel and foreparts with registering slots, connecting mechanism contained within the slots and including a main link having spaced side members longitudinally slotted near one end, an anchor pin in the forepart of the last passing through the slot of the main link, a toggle link movably contained between the side members of the main link and having a pin slidable in said slot and an end face engageable with said anchor pin, a second toggle link pivoted to the other end of the main link and having an intermediate aperture, and an anchor pin in the heel part of the last passing through said aperture.
- 35 2. In a collapsible last having heel and foreparts, connecting mechanism including a longitudinally slotted main link, a pair of toggle links carried by the main link and presenting an abutment movable in the slot of the main link, an anchor pin passing through the slot, and a second anchor pin passing through one of the toggle links.
- 40 3. A collapsible last having heel and foreparts and connecting mechanism including a long slotted link, a pin anchoring it to the forepart, a short toggle link anchored to the heel part and a second toggle link connected to the short link and having a contact face movable in the slot of the long link to push the said anchor pin into last locking position.
- 45 4. A collapsible last having heel and foreparts and connecting mechanism including an anchor pin in each part, a long link having a slot in which the forepart anchor pin is received, and toggle links one of which receives the anchor pin of the heel part and the other has a contact face movable against the other pin in the slot of the long link.
- 50 5. A collapsible last having heel and foreparts and connecting mechanism comprising a single anchor pin only in each part, and tension means for limiting separation of said pins including one toggle link of a pair of links mounted and shaped directly to force the said pins apart, said link being pivotally mounted between its ends to rock on the anchor pin in the heel part of the last.

6. A collapsible last comprising heel and foreparts and connecting mechanism including an anchor pin in each part of the last, a long link having a slot in which one of the anchor pins is freely movable, and a pair of toggle links pivotally connected at one end to the long link, guided at their other end in the slot of the long link and pivotally connected at an intermediate point to the other anchor pin.

7. A collapsible last comprising heel and foreparts and connecting mechanism including anchor pins in each part of the last, a tension link connected directly with one pin, and a pair of toggle links connected at their opposite ends respectively to the tension link and at an intermediate point to the other of said pins.

8. A collapsible last comprising heel and foreparts, an anchor pin in each part, a toggle link pivoted about the heel part pin and having contact surfaces on both sides thereof, a tension link pivoted to the toggle link and having a slot therein in which the forepart pin is freely movable, and a second toggle link pivoted to the

first named toggle link and having a contact portion slidable in the slot of the tension link.

9. A collapsible last comprising heel and foreparts, a single anchor pin only in each part of the last, a slotted tension link engaging the anchor pin of the forepart and being connected also to the heel part, a toggle link pivoted at an intermediate point to rock upon the anchor pin of the heel part, and a second toggle link connected to the toggle link first mentioned and having a sliding connection with the tension link.

10. A collapsible last of the character described in claim 9 in which the sliding connection of the second toggle link with the tension link includes a contact face for engaging the anchor pin of the forepart.
